UNITED STATES PATENT OFFICE.

ALBERT BAUMGARTEN, OF FREEPORT, ILLINOIS.

LEMON-SQUEEZER.

SPECIFICATION forming part of Letters Patent No. 703,517, dated July 1, 1902.

Application filed March 3, 1899. Renewed July 13, 1901. Serial No. 68,251. (No model.)

To all whom it may concern:

Be it known that I, ALBERT BAUMGARTEN, a resident of Freeport, county of Stephenson, State of Illinois, have invented certain new and useful Improvements in Squeezers, of which the following is a full, clear, and exact description.

The present invention relates to devices used for expressing the juice from lemons, limes, and the like, and designs to provide a squeezer which can be produced at a low cost which is simple in construction and efficient in operation.

The invention consists in the several novel features of construction hereinafter set forth, and more particularly defined by claims at the conclusion hereof.

In the drawings, Figure 1 is a view in side elevation of a squeezer embodying the invention. Fig. 2 is a view in central vertical longitudinal section taken on line 2 2 of Fig. 3. Fig. 3 is a plan view, the parts being shown in open position. Fig. 4 is a detail plan of the dish and cone. Fig. 5 is a vertical transverse section on line 5 5 of Fig. 2.

The squeezer comprises two pivotally-connected frame members A and C. Frame member A comprises a supporting-ring *a* and integral standards or legs *a'*, *a''*, and *a'''*, where-
30 by the ring is sustained in elevated position, so an ordinary tumbler or receptacle can be placed beneath to catch the expressed juice. The supporting-ring carries a removable dish and compressing member B, which comprises
35 a flange *b*, adapted to rest on ring *a*, a spout *b'*, extended longitudinally from the dish and having holes *b''* therein, wherethrough the expressed juice can escape to the receptacle beneath the squeezer, and a cone *b'*, having a
40 spiral groove *b''* formed thereon.

The frame member C comprises a cup *c'*, which serves as the other compressing part, and a lever-handle *c*. The pivotal connection comprises two longitudinally-projecting
45 ears or lugs *c'* and *c''*, integrally formed with the supporting-ring *a*, and each of said lugs has an elongated bearing or slot *c''* therein and a pivot-stud *c'*, which is projected laterally from each side of and is integrally formed with a longitudinally-projecting arm of frame member C. Said arm fits loosely between the bearing-lugs and has a slight lat-

eral play therebetween. Pivot *c'* is held in slots *c''*, which are elongated to permit a longitudinal shift of the frame members, so the 55 compressing parts—*i. e.*, the cup and cone—are free to relatively position each other during the vertical travel of the swinging member and the operation of the parts to express the juice and to relatively position each other 60 according to the size and shape of the interposed lemon-section, or, in other words, are permitted free relative self-adjustment during the squeezing operation in a plane substantially perpendicular to the direction of 65 application of the compressing force. Slots *c''* are substantially parallel with their frame member A, and, together with the slight lateral play of the pivot-stud and arm, permit the cup and cone to position each other laterally 70 during the operation of the parts to express the juice from a lemon, lime, or like article held in the squeezer. That portion of the supporting-ring which is between the bearing-lugs is severed or cracked, as shown at 75 *c''*, so the lugs can be spread to permit the arm and pivot-stud to be inserted to be placed, respectively, between and into the bearing-lugs. The bearing-lugs are preferably inclined upwardly and toward each other, so the 80 pivot-stud can be conveniently forced between the lugs and into position to be securely held in slots *c''*.

The operation will be as follows: A lemon-section is held between the cone and cup until the frame members have been brought together to hold the lemon. The lever-handle will then be depressed to express the juice from the lemon. During such shift of the members they will by reason of the loose 85 pivotal connection be free to permit the cup and cone to be guided longitudinally and laterally by each other and according to the size and shape of the lemon-section therebetween, and by reason of the loose pivotal connection the lemon will always be evenly distributed around the cone. The expressed juice will pass from the dish B through the strainer-spout *b'* and into a receptacle beneath the frame. 90 100

The invention possesses numerous advantages. The construction is simple. The pivot-stud and bearing-lugs having the elongated bearings or slots therein are constructed

and arranged so that these can be integrally formed with the frame members and can be quickly assembled and interlocked, so they cannot be disconnected during the usual 5 operation of the squeezer. The necessity of accurately fitting the parts is entirely avoided, since the parts are loosely connected and are positioned during the squeezing operation by the compressing parts.

10 A further important resultant advantage of the invention is that the pivot and elongated slot permit a relative longitudinal shift, whereby the cup and cone will be positioned longitudinally by each other and the interposed lemon or other article. Furthermore, 15 the play of the pivot in its bearings and the longitudinal arrangement of the slots permit a lateral play of the frame members, whereby the cup and cone will be relatively positioned by each other and the interposed lemon. Thus it will be seen that the pivotal connection is such as to permit a limited universal—*i. e.*, both lateral and longitudinal—relative shift of the members during operation, and 20 so the cup will be positioned by the cone and interposed lemon, and therefore the lemon will always be evenly distributed around and between the compressing part, and the lemon will be evenly compressed. This advantage 25 is an important one.

Manifestly the invention provides a squeezer for lemons, limes, and the like which is simple and inexpensive in construction, which is formed of few elements, and which is efficient in operation.

30 The invention is not to be understood as restricted to the details shown and described, but may be varied by the skilled mechanic without departing from the spirit of the invention. So, also, the novel features may be employed severally without adoption in entirety.

Having thus described my invention, what I claim as new, and desire to secure by Letters 45 Patent, is—

1. A fruit-squeezer comprising two compressing members movable relatively toward and from each other, and provided respectively with cup and cone, and connections 50 between said compressing members for allowing longitudinal and lateral relative self-adjustment of said cup and cone during the squeezing operation in a plane substantially perpendicular to the direction of application 55 of the compressing force.

2. A fruit-squeezer comprising two compressing members movable relatively toward and from each other, and provided respectively with a cup and cone, and pivotal connections between said compressing members 60 for allowing longitudinal and lateral relative self-adjustment of said cup and cone during the squeezing operation in a plane substantially perpendicular to the direction of application 65 of the compressing force.

3. A fruit-squeezer comprising two com-

pressing members movable relatively toward and from each other, and provided respectively with a cup and cone, and pivotal connections comprising a pin and an elongated 70 bearing between said compressing members for allowing longitudinally and laterally relative self-adjustment of said cup and cone during the squeezing operation in a plane substantially perpendicular to the direction of 75 application of the compressing force.

4. A fruit-squeezer comprising two compressing members movable relatively toward and from each other, and provided respectively with a cup and cone, and pivotal connections comprising a pin and an elongated bearing between said compressing members for allowing longitudinally and laterally relative self-adjustment of said cup and cone 80 during the squeezing operation in a plane 85 substantially perpendicular to the direction of application of the compressing force, said bearing being substantially parallel with the compressing members when in closed position.

5. A fruit-squeezer comprising two compressing members movable relatively toward and from each other and provided respectively with a cup and cone, and pivotal connections between said compressing members for allowing free relative self-adjustment of 90 said cup and cone during the squeezing operation in a plane substantially perpendicular to the direction of application of the compressing force, said connections comprising a pin and an elongated bearing, said pin having limited lateral play in said bearing.

6. In a squeezer, the combination of two pivotally-connecting members and a lemon-supporting dish sustained in one of said members, the latter member being provided with 105 a circular ring to receive said dish and a pair of lugs extending longitudinally therefrom upon the side opposite the handle, the metal of the ring being severed to permit them to spring apart, and the other member being 110 provided with a pivot-stud extending laterally from each side thereof, and fitted to said ears, whereby said pivot may be sprung between and into the ears by reason of the elasticity of said ring.

7. A squeezer, comprising a supporting dish, a supporting member therefor, having a dish-supporting ring, lugs upon one side of said ring, the material of the ring being separated between the lugs and a second member having pivot-studs fitted in said ears whereby the elasticity of the ring is utilized in springing the members into pivotal connection.

In witness whereof I have hereunto set my hand, at Freeport, in the county of Stephenson and State of Illinois, this 24th day of February, A. D. 1899.

ALBERT BAUMGARTEN.
